DESIGN FOR A CONTAINER

Carl Preis, New York, N. Y., assignor to American
Can Company, New York, N. Y., a corporation
of New Jersey

Application September 16, 1939, Serial No. 87,257

Term of patent 14 years

To the Commissioner of Patents:

Be it known that I, Carl Preis, a citizen of the United States of America, residing at 405 Park Avenue, in the city of New York, county of New York, and State of New York, have invented a new, original, and ornamental Design for a Container, of which the following is a specification, reference being had to the accompanying drawing, forming a part thereof.

Figure 1 is a perspective view of a container embodying the instant design, the view showing the top of the container; and

Fig. 2 is a perspective view of the bottom of the container, the upper portion of the container being broken away.

The characterizing feature of my design resides in a container of the configuration disclosed having a closure member of the specific configuration shown.

I claim:

The ornamental design for a container, as shown and described.

CARL PREIS.
